UNITED STATES PATENT OFFICE.

WILLIAM M. HOFFMAN, OF BUFFALO, NEW YORK, ASSIGNOR TO GENERAL FUEL APPARATUS CORPORATION, OF BUFFALO, NEW YORK, A CORPORATION OF DELAWARE.

FUEL-OIL BURNER.

1,378,115.

Specification of Letters Patent. Patented May 17, 1921.

Application filed March 5, 1920. Serial No. 363,547.

To all whom it may concern:

Be it known that I, WILLIAM M. HOFFMAN, a citizen of the United States, residing at Buffalo, county of Erie, State of New York, have invented a certain new and useful Improvement in Fuel-Oil Burners, and declare the following to be a full, clear, and exact description of the same, such as will enable others skilled in the art to which it pertains to make and use the same, reference being had to the accompanying drawings, which form a part of this specification.

This invention relates to improvements in fuel oil burners and particularly to that type of burner designed to utilize the heavier hydro-carbons in which a considerable amount of asphalt material is found. The burner is so constructed that a forced air draft will be drawn along the face of the opposed burner plates through the dense portion of the flame and it is further designed to utilize superheated steam in order to produce a more nearly perfect combustion of the fuel.

25 In the drawings—

Figure 1 is a vertical sectional view of my improved form of burner.

Fig. 2 is a horizontal view taken on the line II—II of Fig. 1.

30 Let *a* represent the base of the apparatus designed to support burner plates herein-after described and adapted in turn to serve as a drip-pan being partially filled with a refractory porous substance such as asbestos indicated as *b*, upon which the oil that falls from the superimposed burner plates may be burned.

An outlet pipe *e* leads from the receptacle *a* to a sump, not shown in the drawings. 40 The flow of oil therethrough is regulated by means of a valve *e*². The burner plates carried by this base *a* comprise frame members *b* and *c* each in the form of a box cut in half adapted to contain a refractory substance indicated as *b*², *c*² respectively. These frame portions *b* and *c* are disposed in parallel vertical planes opposed to each other and fastened together by means of tie-bolts *f*, *f*² passed through opposed projecting ears 45 carried by said frame members. These tie-bolts are four in number, two on each side of the apparatus.

The porous refractory material which is carried by each of these half box portions

b and *c* is respectively indicated as *b*² and *c*² 55 and forms the burner plate proper which is supplied with fuel oil from a perforated trough-shaped shelf *g* positioned above the plate, which is carried by each frame portion, and which is in turn supplied with fuel from feed pipes *h*. These feed pipes are four in number, as shown in Fig. 2 and the flow of fuel therethrough may be regulated by means of valves *i*. The fuel oil passes from the feed pipes *h* into the trough *g* and through the perforated floor of the trough to the porous refractory plate there-beneath carried by the frame. 60 65

After a certain amount of oil has been supplied to this trough *g* if, due to an over-supply in quantity or to slow-seeping action through the refractory burner plate, it does not pass through the perforated floor thereof, it will flow over the flanged edge of the trough and down along the face of the burner plate where it may be burned. 70 It will be noticed that the plate *c*² which carried the nozzle *j* is provided with a groove *c*³ hereinafter more particularly referred to. 75

From the rear through the plate *c*² a nozzle *j* provided with a regulator needle valve *j*² is projected. This nozzle passes through the face of the burner plate so as open approximately centrally therein the air passageway between the two burner plates. 80 A supply conduit *k* leads to this nozzle, which conduit is provided with a main branch *k*² which leads to a source, not shown in the drawings, from which is drawn a supply of air under pressure. 85 The flow of air through the conduit *k*² may be regulated by means of valve *k*³. 90

A combustion chamber 1 is provided 95 which passes through the burner plate *b*² opposite the nozzle *j* carried by the plate *c*². This combustion chamber 1 is in the form of a funnel increasing in diameter as it proceeds outwardly. The outer extension of the combustion chamber is formed with a jacketed wall *l*² adapted to serve as a steam superheater. Steam is supplied from this superheater to the nozzle through the conduit *m* which leads to the main conduit *k* leading to the nozzle. The flow of steam 100 through the pipe *n* is regulated by means of the valve *n*².

It will be observed that the burner plates

are so tied together that an air passageway is provided between them opening to the atmosphere on all four sides.

In the operation of this device fuel oil is supplied through the pipes *h* to troughs *g*. The oil passes down through the perforated floor of the trough *g* and by virtue of the porous character of the refractory burner plate it seeps through and out upon the face thereof where it is burned. When the burner is first started, in order to secure combustion it will be found desirable to furnish air under pressure through the nozzle *j* without the addition of any stream thereto. As the combustion proceeds and the oil is supplied in greater quantity, superheated stream is furnished through the conduit *m* from the superheater *l* to the nozzle. The projection of a steam or air jet through the nozzle *j* would create a forced draft between the two burner plates drawing in the air from all sides and the products of combustion will be projected outwardly through the funnel-shaped passageway in the opposite burner plate into the combustion chamber *l* where the volatilized burning products of hydro-carbon will be so thoroughly mixed with the air drawn through the passageway between the burner plates *b*² and *c*² and with the steam projected through the nozzle that combustion of an exceedingly high degree will result.

In the passage of the burning particles through this combustion chamber *l* the steam carried in the jacketed wall will be superheated and conducted to the nozzle *j*. This ensures at the nozzle a high quality of superheated steam and by regulating the supply of steam to this superheater steam of a high, dry quality and of practically constant quantity will be supplied to the nozzle.

In burners of this character, it is found that to secure a high quality of combustion it is necessary that the oxygen of the air and hydrogen which would be furnished by way of steam be mixed with the volatilized hydro-carbon in combustion by being passed through the dense portion of the flame. These vertical burner plates therefore are so spaced from each other that the burning particles of hydro-carbon formed by the volatilized oil burning on the face of each plate will be mixed with oxygen drawn through the central air passageway under forced draft at that point where the flame is most dense. A distinct function is served by the provision of the opposed burner plates. If but one plate were provided, the air drawn in through this air passageway would pass along the wall opposite the burner plate rather than along the face of the plate and would not mix with the products of combustion in the manner desired.

65 The groove *c*³ previously referred to ex-

tends partially circumferentially of the nozzle *j* and is designed to prevent oil flowing along the face of the burner plate from entering the nozzle clogging the same and preventing the passage of air therethrough. The groove *c*³ is of greater extent than a half circle, so that it will extend down below the nozzle opening, in order that any oil that might run into the groove may be carried away so as not to fill up the nozzle opening.

It will be observed that any oil which might drip from the burner plates *b*₂ and *c*₂ into the drip-pan *a* would be consumed on the surface of the filler *d* carried in such drip-pan. Should oil in excess quantity be allowed to collect in this drip pan *a* it might be drawn therefrom through the outlet pipe *e*.

Claims:

1. In a fuel oil burner, a drip-pan containing a porous refractory filler and provided with a discharge conduit leading therefrom, a pair of parallel opposed vertical burner plates, spaced from each other so as to provide an air passageway therebetween supported over said drip-pan in such a manner as to provide a circumferential air inlet-opening to said drip-pan, said burner plates composed of refractory porous material, means for supplying fuel oil to said burner plates, said plates so adapted that said oil may gravitate therethrough and seep out along the face thereof, a nozzle adapted to project a vapor jet through one of said plates into the air passageway therebetween, a combustion chamber passing through the other of said burner plates disposed opposite the nozzle.

2. In a fuel oil burner, a pair of opposed vertical burner plates composed of porous refractory material and spaced from each other so as to provide an air passageway therebetween, a perforated oil trough positioned at the top of each of said burner plates, means for supplying oil thereto, said burner plates so formed that the oil passing from said trough thereto will gravitate through said plates and seep out upon the face thereof, means for projecting a vapor jet through one of said plates into the air passageway therebetween, the other of said plates adapted to permit the passage of the products of combustion therethrough opposite said jet projecting means and provided with a mixing chamber.

3. In a fuel oil burner, a pair of opposed vertical burner plates spaced from each other so as to provide an air passageway therebetween, said plates composed of a porous refractory material adapted to permit the gravitation of fuel oil therethrough so that it may seep out upon the face thereof, a perforated oil trough adjacent the top of each of said burner plates adapted to receive oil and to permit the oil to pass

through the perforations thereof to said burner plates, a nozzle carried by one of said burner plates approximately centrally thereof adapted to project a vapor jet into 5 the air passageway between said plates, a combustion chamber carried by the other of said plates opposite the nozzle, adapted to permit the passage of the products of combustion therethrough and provided with a 10 jacketed wall for a portion of its distance, means for supplying steam to the jacketed wall of said combustion chamber, means for conducting steam from said jacketed wall to the nozzle, means for conducting air under 15 pressure to said nozzle.

4. In a fuel oil burner, a pair of opposed vertical burner plates composed of a porous refractory substance and spaced from each other so as to provide an air passageway 20 therebetween open on all sides, means for supplying fuel oil to the top of said burner plates, means for creating a forced draft through the air passageway between said plates by projecting through one of said 25 plates a vapor jet, means for permitting the products of combustion to be projected through the other of said plates, into a combustion chamber, said chamber, disposed opposite said vapor projecting means carried 30 by the opposite plate.

5. In a fuel oil burner, a drip-pan containing a refractory porous material, a pair of opposed parallel vertical burner plates, a circumferential air passageway leading to 35 said drip pan around the outside of said burner plates, said burner plates spaced from each other so as to provide an air passageway therebetween open on all sides, an oil trough positioned at the top of each 40 of said burner plates adapted to receive oil and to permit the passage of oil therethrough to said plates, means for supplying oil to said trough, said plates so adapted as to permit the gravitation of oil therethrough

and its seeping out upon the face thereof, means for creating a forced draft between said plates, means for projecting the products of combustion from between said plates through one of said plates into a combustion chamber.

6. In a fuel oil burner, a drip-pan containing a porous refractory material, a pair of vertically opposed burner plates spaced from each other so as to provide an air passageway therebetween and supported 55 above said drip-pan, an oil trough adapted to receive oil positioned above each of said burner plates and perforated to permit the passage of oil therethrough to the plate beneath, said plates adapted to permit the 60 gravitation of oil therethrough and out along the face thereof, a nozzle carried by one of said plates adapted to project a jet of vapor into the air passageway between said plates, the other of said plates provided 65 with a passageway through which the products of combustion may pass, means for supplying air under pressure to said nozzle, means for supplying superheated steam under pressure to said nozzle. 70

7. In a fuel oil burner a pair of opposed vertical burner plates composed of refractory porous material positioned so as to be spaced from each other forming an air passageway between such plates, means for 75 supplying fuel oil to the top of such plates so that such oil may percolate therethrough and seep out on the face of the plates, means for projecting a vapor jet through one of said plates into the air passageway 80 between the plates, the other of such plates provided with a combustion chamber extending through the plate and positioned opposite the vapor jet projecting means.

In testimony whereof, I sign this specification. 85

WILLIAM M. HOFFMAN.
